(57) CLAIM

The ornamental design for a pedicure spa, as shown and described.

DESCRIPTION

FIG. 1 is a front perspective view of a pedicure spa showing our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a front perspective view of the pedicure spa including a sink attached thereto, the sink being shown in broken lines.

The broken line showing of parts of the drawings is included for the purpose of illustrating use and environment and forms no part of the claimed design.

1 Claim, 5 Drawing Sheets
